PLAYGROUND CANOPY

George H. Goundie and Howard C. Schroedter, Milwaukee, Wis., assignors to Creative Playstructures, Inc., Milwaukee, Wis., a corporation of Wisconsin

Application November 20, 1956, Serial No. 43,842

Term of patent 7 years

(Cl. D34—15)

FIG. 1

FIG. 2

FIG. 4

Fig. 1 is a perspective view of a playground canopy, showing our new design;

Fig. 2 is a side elevational view, the opposite side being substantially a mirror image thereof;

Fig. 3 is an end elevational view, the opposite end being substantially a mirror image thereof, and

Fig. 4 is a top plan view.

We claim:

The ornamental design for a playground canopy, substantially as shown and described.
